UNITED STATES PATENT OFFICE.

CHARLES E. GREEN, OF ST. AUGUSTINE, FLORIDA.

OIL-BURNER.

1,347,458.

Specification of Letters Patent. Patented July 20, 1920.

Application filed June 24, 1919. Serial No. 306,504.

To all whom it may concern:

Be it known that I, CHARLES E. GREEN, a citizen of the United States, residing at St. Augustine, in the county of St. Johns and State of Florida, have invented certain new and useful Improvements in Oil-Burners; and I do hereby declare the following to be a full, clear, and exact description of the invention, such as will enable others skilled in the art to which it appertains to make and use the same.

This invention relates to fuel burners and more particularly to an improved type of oil burner.

15 It is an object of the present invention to provide an improved and simple type of burner readily adaptable for the combustion of light and heavy oils.

20 A further object of the invention is to provide a construction of few and simple parts which can be readily assembled and easily replaced when renewal is necessary.

25 A further object of the invention is to provide a device of this kind which is shown organized and so constructed that the parts will have considerable length of light and which can be adjusted and assembled with ease by a person of average intelligence thus making the device capable of use in an extremely large field for the burning of various grades and kinds of oil.

30 With the above and other objects in view as will be rendered manifest to those versed in the art, the invention consists of the construction, combination, and in details and arrangements of the parts as more particularly described in the following specification relative to the embodiment of the invention disclosed in the accompanying drawings, in which:

35 Figure 1 is a side elevation of the burner with a portion in vertical central section.

Fig. 2 is a transverse vertical section on the longitudinally medial plane.

40 Fig. 3 is a plan view of the burner partly broken away to show the air regulator.

Fig. 4 is a perspective view of the air regulator and

45 Fig. 5 is a detailed sectional view of an adapter attachable to the oil nozzle.

In the illustrated embodiment of the in-

vention the burner consists of an air chamber having upper and lower sections 2 and 3 having complementary inter-engaging edges designed to make an approximately 55 and sufficiently tight joint, both to keep the parts in proper register when assembled and to prevent the admission of air into the chamber at the joint. The bottom section 3 is provided with a perforated bottom 5 60 and slidably arranged just below the bottom is a gate or regulator 6 perforated as at 7 to register with the perforations 8 in the bottom 5. One end of the regulator 6 is provided with a suitable part 9 to be engaged by the user of the burner to enable it to be adjustable with respect to the apertures 8 so as to control the quantity of air admitted into the air chamber.

Oil to be consumed in the burner may be 70 supplied from any suitable source connections being made with the feed pipe 10 which extends upwardly through the slot 11 in the regulator and through the support 12 on the bottom 5. The pipe is shown as 75 provided with end or nozzle sections 13 which may be fastened or secured in place by any suitable means, as for instance, by a set screw 14 in the support or guide 12.

The upper end of the nozzle is shown as 80 threaded as at 15, to receive a mixer or baffle 16 which has a divergent surface and which is provided in its top with a pocket 17 to catch such oil as may overflow. The baffle 16 which is threaded upon the upper 85 end of the said pipe is preferably adapted for catching the surplus oil, should the oil be fed through the pipe faster than the combustion takes place in the adapter. The mixer or member 16 is disposed within a 90 downwardly convergent basin 18 to the lower and open end of which may be secured an air feeder 19 open at its lower end and provided with openings 20 through which air going into the chamber will pass upwardly and around the nozzle 13, thence passing through the annular space between the basin 18 and the baffle 16 over which it is directed into an upper extended combustion box 21 in the form of a cylinder suitably mounted upon the top section 2 and preferably attached thereto by suitable 100

means as screws or bolts 22 which pass through lateral extensions from the body of the box 21.

For the purpose of adapting this burner 5 for the combustion of oil of different qualities, there is attachable to the upper end of the nozzle 13 a headpiece or adapter tip 23. These adapters are generally provided 10 in sets, each set differing from the other in the size of the adapter through which the oil issues when admitted to the supply pipe 10 so that they may be readily interchanged, according to the type of fuel being used. In Fig. 2, the adapter tip is designated at 23 15 as threaded to the upper end of the nozzle and as having a relatively large outlet 24 for the burning, for instance, of crude oil. In Fig. 5, the adapter tip 23 is provided with a relatively small aperture 24, as for 20 the burning of light oil.

When the oil is turned on and ignited in the tip 23, the deflector 25 which extends laterally across and above the box 21 is thrown to the side upon its support 26. As 25 soon as effective combustion starts, the deflector can again be swung around into position over the outlet of the box 21.

From the above, it will be seen that air to supply combustion is admitted through 30 the perforated bottom 5 and controlled by the slidable regulator 6. The air passes upwardly into the basin 18, converges over the top of the baffle 16 and passes between the edge of the tip 23 and the bottom of the 35 box 21, so that fresh air is thoroughly intermixed with the gases produced by the combustion of the fuel and the state of combustion is effectively active in the box 21, said box being easily cleaned of carbon that 40 collects therein.

What I desire to claim is:

1. An oil burner comprising an air chamber having two sections, one forming the top and one forming the bottom, the lower 45 section having a perforated bottom; an air regulator adjustably mounted on the bottom to control the admission of air into the chamber through the perforated bottom; an oil feed pipe extending up into the chamber; 50 a basin with an open bottom surrounding the upper end of the feed pipe; a baffle mounted on the upper end of the feed pipe and spaced from the inner surface of the basin; and a combustion or fire box above 55 the upper end of the feed pipe; and an adapter adjustable to the discharge end of the feed pipe to adapt the burner to the combustion of a given grade of oil.

2. An oil burner comprising an air chamber having two sections, one forming the top and one forming the bottom, the lower section having a perforated bottom; an air regulator adjustably mounted on the bottom to control the admission of air into the 60 chamber through the perforated bottom; an 65 adapter

oil feed pipe extending up into the chamber; a basin with an open bottom surrounding the upper end of the feed pipe; a baffle mounted on the upper end of the feed pipe and spaced from the inner surface of the 70 basin; and a combustion or fire box above the upper end of the feed pipe; and an adapter adjustable to the discharge end of the feed pipe to adapt the burner to the combustion of a given grade of oil; and a 75 baffle having a central chamber into which excess oil may flow from the adapter.

3. An oil burner comprising an air chamber having two sections, one forming the top and one forming the bottom, the lower 80 section having a perforated bottom; an air regulator adjustably mounted on the bottom to control the admission of air into the chamber through the perforated bottom; an oil feed pipe extending up into the chamber; a basin with an open bottom surrounding the upper end of the feed pipe; a baffle mounted on the upper end of the feed pipe and spaced from the inner surface of the 85 basin; and a combustion or fire box above the upper end of the feed pipe; and an air feeder at the bottom of the basin through which the feed pipe extends.

4. An oil burner comprising upper and lower sections, a downwardly converging 90 basin in the upper section, a feed pipe extending into the basin, a baffle on the upper end of the feed pipe and spaced from the wall of the basin, means for admitting air to the space between the basin and baffle and a combustion or fire box above the upper end of the feed pipe.

5. An oil burner comprising upper and lower sections, a downwardly converging basin in the upper section, a feed pipe extending into the basin, an adapter detachably secured to the discharge end of the feed pipe to adapt the burner to the combustion of a given grade of oil, means for admitting air to the lower end of the basin so 105 that air passing upwardly will be intermixed with the gases produced by combustion in the combustion or fire box above the upper end of the feed pipe.

6. An oil burner comprising a main chamber, a downwardly converging basin in the top wall of said chamber, a feed pipe extending upwardly through the chamber and into said basin and an air feeder at the bottom of the basin through which the feed 110 pipe extends.

7. An oil burner comprising a main chamber, a downwardly converging basin in the upper wall of said chamber, a feed pipe extending through the chamber upwardly into 125 the basin, an adapter, detachably secured to the discharge end of the feed pipe, to adapt a burner to the combustion of a given grade of oil and an air feeder at the bottom of the basin through which the feed pipe extends 130

so that the air passing upwardly around the adapter will be intermixed with the gases produced by combustion.

8. An oil burner comprising a supporting body, a basin in the top wall of said body, a feed pipe extending upwardly through the body and into the basin, means for feeding

air into the basin around the feed pipe and a baffle arranged above the air inlet in the basin for intermixing the air with the gases 10 produced by combustion.

In testimony whereof I affix my signature.

CHARLES E. GREEN.
